UNITED STATES PATENT OFFICE.

CHARLES MARKEL, OF CLINTON, IOWA.

CONNECTING-ROD.

1,010,287.

Specification of Letters Patent. Patented Nov. 28, 1911.

Application filed June 13, 1910. Serial No. 566,616.

To all whom it may concern:

Be it known that I, CHARLES MARKEL, a citizen of the United States, residing at Clinton, in the county of Clinton and State of Iowa, have invented new and useful Improvements in Connecting-Rods, of which the following is a specification.

The present invention has reference to improvements in locomotive main rods, and more especially in or relating to the construction of the so-called brasses or bearings for the rear end thereof, and the therewith-associated parts.

Briefly stated, it comprehends an improved bearing construction wherein the objectionable features ordinarily existent are omitted, and wherein the amount of hand work requisite is practically negligible, and improved filling devices for holding the bearing in place in the rod end.

A structural embodiment of the invention is illustrated in the accompanying drawing, whereof

Figure 1 is a side elevation of the rear end of a locomotive main rod equipped with the afore-mentioned improvements; Fig. 2 is a horizontal longitudinal section of Fig. 1; and Figs. 3 and 4 are plan and side views, respectively, of the bearings shown in Figs. 1 and 2.

In said drawing, 1 indicates, generally, the main rod, which may be of any conventional type, and 2 the solid rear head thereof. Said head is provided with the customary opening 5 which receives the bearing 4 and its associated parts, the inner end of the opening, (i. e., the end nearest the stem or body of the rod), being slightly enlarged at its top and bottom, as indicated by the numeral 5' in Fig. 1. To produce this enlargement, the inner faces of the top and bottom walls of the head may be cut away at the point indicated, as will be understood.

The bearing 4, above referred to, consists of mating or counterpart members 4^a and 4^b of true semi-annular shape, the lines of separation therebetween being transverse to the axis of the rod. The outer peripheral walls of these members are formed with thickened portions or treads 4^c, the edges of which terminate short of the adjacent edges of said walls, thereby producing front and rear shoulders 4^d. In order to permit them to fit squarely within the head opening 5 in such a manner as to be incapable of turn-

ing, the bearing members are planed at top and bottom, as indicated by the character 4^e, the planed faces being disposed at right angles to the lines of separation between said members. The shoulders 4^d merge into said planed faces. To hold the bearing members in place in said head opening, the outer and inner filling blocks 6 and 7 are provided. The block 6 is of the same height 65 as the head opening, and its top and bottom faces are preferably flat or plane and fit against the adjacent walls of said opening; its inner face is concaved to fit the curvature of the bearing member 4^a and is formed 70 at the front and rear edges thereof with lateral flanges 6^a which overlie and engage the shoulders 4^d on said member, while its outer face is formed at its front and rear edges with lateral flanges 6^b, which overlie 75 the corresponding faces of the end member of the rod head. The other filling block 7 is likewise formed with a concave inner face, to fit the curvature of the bearing member 4^b, having front and rear lateral 80 flanges 7^a at its side edges, which flanges overlie and engage the shoulders 4^d on that member; block 7 is, also, of the same height 85 as the head opening, but its top and bottom faces are formed at their front and rear 90 edges with upstanding flanges 7^c which overlie the corresponding faces of the top and bottom members of the head, the enlargements 5' in the head opening being provided to enable said block to be slipped thereinto 95 and then moved laterally toward the bearing, thereby effecting the engagement of its flanges 7^a and 7^c with the parts specified. The remainder of the head opening is occupied by a pair of blocks 8 and 10, of 100 which the first-named is in the form of a wedge, its inclined working face co-acting with the correspondingly inclined or beveled outer side face of block 7. This wedge is mounted on a bolt 9 which serves to produce its requisite longitudinal movement. Block 10 is interposed between the opposite face of the wedge and the adjacent wall of the head opening, and is in the nature of a liner; its height is the same as that of the 105 enlarged portion of the head opening and its flat top and bottom faces fit against the adjacent walls of the enlargement, while its outer face is formed with flanges 10^a 110 similar to the flanges 6^b above referred to.

In assembling the various parts, the block 6 is fitted in the outer end of the head open-

ing 5 with its outer flanges 6^b overlapping the adjacent faces of the head; the two bearing members 4^a and 4^b are next inserted in the opening and moved against block 6, the flanges 6^a on the latter overlapping and engaging the shoulders 4^d on the member 4^a; the block 7 is next slipped into the enlargement 5' of said opening and then moved into said opening and toward the bearing 10 until its flanges 7^a engage the shoulders 4^d on the bearing member 4^b, the top and bottom flanges 7^c of said block engaging the adjacent faces of the corresponding members of the head; the liner 10 is next fitted in the 15 enlarged inner end of the head opening, with its flanges 10^a overlapping the opposite faces of said end; the wedge 8 is then interposed between the parts 7 and 10, and its operating bolt 9 finally inserted in place. 20 When so disposed, all parts will be securely held in position and will be prevented from movement of any character beyond that occasioned by the operation of the wedge incidental to taking up wear upon the bearing 25 members. They may, however, be readily and quickly disassembled by proceeding in the reverse manner to that above described. So far as the bearing members themselves are concerned, it will be observed that they 30 possess no flanges, and, for that reason, are not open to injury; moreover, they can be turned off on a lathe, require no shaping or hand-fitting, and, consequently, can be constructed at a relatively low cost.

35 I claim as my invention:

The combination, with a locomotive main

rod provided at its rear end with a solid head having an opening therein; of a pair of filling blocks disposed within said opening and having their presented inner faces 40 concaved and formed at their front and rear edges with lateral flanges, one of said blocks having the front and rear edges of its outer face formed with lateral flanges which overlie the corresponding faces of the 45 adjacent end wall of said head, and the other block having its top and bottom faces formed at the front and rear edges thereof with lateral flanges which overlie the corresponding faces of the top and bottom 50 walls of said head, said opening having a portion thereof enlarged to permit the introduction of the last-named block thereto; a bearing interposed between said blocks and consisting of a pair of mating semi-annular members having their top and bottom portions planed off to prevent their turning in said opening and having peripheral shoulders merging at their ends into 55 said planed portions, the flanges on the presented inner faces of said blocks engaging said shoulders; and means disposed within said opening and co-acting with one of said blocks for taking up wear in said bearing members.

In testimony whereof I have hereunto set my hand in presence of two subscribing witnesses.

CHARLES MARKEL.
